(74) *Attorney, Agent, or Firm* — Philip L. Bateman

(57) **CLAIM**

The ornamental design for a spool holder, as shown and described.

DESCRIPTION

FIG. 1 is a front, top, and right side perspective view of a spool holder showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof;

FIG. 8 is a front, top, and right side perspective view thereof showing the holding of a spool;

FIG. 9 is a front elevation view thereof showing the holding of a spool;

FIG. 10 is a rear elevation view thereof showing the holding of a spool;

FIG. 11 is a right side elevation view thereof showing the holding of a spool;

FIG. 12 is a left side elevation view thereof showing the holding of a spool;

FIG. 13 is a top plan view thereof showing the holding of a spool;

FIG. 14 is a bottom plan view thereof showing the holding of a spool; and,

FIG. 15 is a front, top, and right side perspective view thereof showing the holding of a spool and the attachment to a vertical surface.

The broken lines showing a spool in FIGS. 8 to 15 are for illustration purposes and form no part of the claimed design. The broken lines showing a vertical surface in FIG. 15 are for illustration purposes and form no part of the claimed design.

1 Claim, 9 Drawing Sheets
